REACTION PRODUCTS OF PRIMARY FATTY AMINES AND KETOSE SUGARS

John G. Erickson, Minneapolis, Minn., assignor to General Mills, Inc., a corporation of Delaware

No Drawing. Application November 26, 1952,
Serial No. 322,812

6 Claims. (Cl. 260—211)

The present invention relates to new compounds obtained by the reaction of fatty amines with ketose sugars and to the process of producing these compounds. These compounds contain a minimum of two fatty amino groups per molecule and may contain a number of fatty amino groups equivalent to the number of carbon atoms in the ketose sugar. The compounds vary in their properties with the number of fatty amine groups. The lower members of the group (those containing 2 or 3 fatty amino groups per molecule) can be used directly as surface active agents or may be converted into other surface active agents by suitable reactions, such as sulfation, hydrogenation and the like. The compounds containing larger numbers of fatty amino groups may be used to waterproof textiles, either by direct deposition on the fabric or by reaction with formaldehyde and subsequent insolubilization on the cloth.

It is, therefore, an object of the present invention to provide novel reaction products of fatty amines and ketose sugars in which the compounds contain at least two fatty amino groups per molecule.

It is another object of the present invention to provide a process of producing such compounds.

The invention is applicable to ketopentoses, keto-hexoses and ketoheptoses. Suitable sugars which may be used in the present invention include fructose, sorbose, tagatose, psicose, xyloketose, riboketose, sedoheptose, mannoketoheptose, perseulose and glucoheptulose. By means of the present invention it is possible to introduce a fatty amino group onto each carbon atom of the ketose sugar.

The fatty amines which may be used include the primary amines, either saturated or unsaturated, containing from 8-22 carbon atoms. These may be single, isolated amines, or may be mixed amines derived from the fatty acids of a fat or oil, or from any selected group of such fatty acids.

In preparing these products it is desirable to use an excess of amine over the theoretical quantity of amine required to introduce the desired number of fatty amino groups into the sugar. The introduction of two fatty groups into the molecule may be attained even without the employment of an excess of amine. For example, octadecylamine and fructose in equimolar quantities yield the dioctadecylamino fructose compound merely upon allowing the mixture to stand at room temperature for 24 hours. However, even in this instance it is preferred to use a ratio of at least 2 mols of amine to 1 of sugar. Where it is desired to introduce higher numbers of fatty amine groups, it is preferred to use still higher ratios of amine to sugar; for example, as high as 8 to 10 mols of amine per mol of sugar where it is desired to introduce 5 or 6 fatty amino groups.

Room temperature is satisfactory for the introduction of two fatty amino groups into the sugar molecule. In order to obtain more highly substituted products it is preferred to heat the reactants together at temperatures within the range of 30–100° C. Temperatures in excess

of 100° C. tend toward excessive decomposition. The preferred temperature range is 50–80° C. The time required depends upon the temperature used and the product desired. For example, from 10–20 hours are suffi-

5 cipient at room temperature to introduce 2 fatty amino groups. To introduce 3 or 4 fatty amino groups requires more drastic conditions. To introduce 6 fatty amino groups into fructose, for example, may require from 4-6 hours at 70° C.

10 The reaction is preferably carried out in the presence of an aqueous solvent such as a mixture of water and a lower aliphatic alcohol. Alcohols such as methyl, ethyl, propyl, isopropyl and the like are suited for this purpose.

There are numerous possibilities for the structure of these compounds and for the course which the reaction takes. The following reactions indicate the courses which the reaction may take and the products which may be obtained.

45 These reactions may continue until all oxygen in the sugar has been replaced by nitrogen. Obviously, a large number of different compounds is possible. Not only the straight-chain forms shown above can be formed, but also others such as:

Besides these straight-chain forms, one can get their cyclized forms. Some of these are:

Example 1

70 A solution of 5.4 parts of fructose and 11.1 parts of dodecylamine in a mixture of equal volumes of water and isopropyl alcohol was allowed to stand at room tem-

perature for 10 days. It was then filtered and the reaction product was recrystallized from a low-boiling paraffin hydrocarbon. The pure product melts with decomposition at 103.5-104.5° C. Analysis showed that it had been formed by the reaction of 2 mols of dodecylamine with 1 mol of fructose.

Example 2

A solution of 26.9 parts of octadecylamine and 18 parts of fructose in a mixture of two volumes of isopropyl alcohol and one volume of water was allowed to stand at room temperature for two days. The mixture was filtered, giving a crude product. After two recrystallizations from alcohol and ethyl acetate, it melted with decomposition at 105.2-106° C. Analysis showed that it had been formed by the reaction of two mols of amine for each mol of sugar.

Example 3

A solution of 26.9 parts of octadecylamine and 9.0 parts of sorbose in a mixture of 2 volumes of isopropyl alcohol and 1 volume of water was allowed to stand at room temperature for four days. It was then filtered. The product after recrystallization from alcohol and ethyl acetate, melted (with decomposition) at 69-71° C. Analysis showed that it was a mixture of the reaction products of 1 mol of sorbose with 2 and with 3 mols of amine.

Example 4

A solution of 26.9 parts of octadecylamine and 2.70 parts of sorbose in a mixture of 4 volumes of isopropyl alcohol and 1 volume of water was heated to 60-70° once on each of 26 days, then allowed to cool. It was filtered and the product was recrystallized from alcohol, M. P. 63.5-65° C. Analysis showed that between 4 and 5 mols of amine had reacted with each mol of sugar.

Example 5

A mixture of 3 parts of the reaction product of Example 4 and 3 parts of octadecylamine in benzene was heated at 80° C. for 6 hours, cooled and filtered. Evaporation of the filtrate, followed by recrystallization of the residue from alcohol, gave a product, M. P. 67-69.5° C. Analysis showed that it had been formed by reaction of 5 mols of amine with 1 of sugar.

Example 6

Four parts of the reaction product of Example 4 and 4 parts of octadecylamine were dissolved in isopropyl alcohol. The mixture was heated two hours at 80° C., cooled and filtered. Recrystallization from a methanol-isopropyl alcohol mixture gave a product, M. P. 65-67° C. Analysis showed that between 5 and 6 mols of amine had reacted for each mol of sugar.

Other ketone sugars containing 5-7 carbon atoms may

be substituted for the sugars disclosed in the examples with similar results.

I claim as my invention:

1. A ketose sugar-fatty amine reaction product, the ketose sugar containing from 5-7 carbon atoms, the fatty amine containing from 12-18 carbon atoms and the reaction product containing a number of fatty amino groups varying from 2 to the number of carbon atoms in the ketone sugar.

10 2. A fructose-fatty amine reaction product, the fatty amine containing from 12-18 carbon atoms and the reaction product containing from 2-6 fatty amino groups.

15 3. A sorbose-fatty amine reaction product, the fatty amine containing from 12-18 carbon atoms and the reaction product containing from 2-6 fatty amino groups.

4. Process of preparing ketose-fatty amine reaction products containing at least 2 fatty amino groups which comprises reacting a ketose containing from 5-7 carbon atoms with a fatty amine containing from 12-18 carbon atoms, the fatty amine being employed in excess of the theoretical quantity required for the introduction of the desired number of fatty amino groups, at a temperature within the range of 40 to 100° C.

5. Process of producing ketose-fatty amine reaction products which comprises reacting a ketose containing from 5-7 carbon atoms with a fatty amine containing from 12-18 carbon atoms in the range of 50 to 80° C. in the presence of at least 2 mols of amine per mol of ketose.

30 6. Process of producing ketose-fatty amine reaction products which comprises reacting a ketose containing from 5-7 carbon atoms with a fatty amine containing from 12-18 carbon atoms, the fatty amine being employed in a molar ratio at least 3 times that of the ketose at a temperature within the approximate range of 50-80° C.
